UNITED STATES PATENT OFFICE.

CLARENCE H. CALDWELL, OF OAK PARK, ILLINOIS.

COPYING PROCESS AND APPARATUS FOR TYPEWRITERS.

Continuation of application Serial No. 411,519, filed September 20, 1920. This application filed September 18, 1922. Serial No. 588,754.

To all whom it may concern:

Be it known that I, CLARENCE H. CALDWELL, a citizen of the United States, and a resident of the village of Oak Park, in the 5 county of Cook and State of Illinois, have invented certain new and useful Improvements in a Copying Process and Apparatus for Typewriters; and I do hereby declare that the following is a full, clear, and exact 10 description of the same, reference being had to the accompanying drawings and to the numerals of reference marked thereon, which form a part of this specification.

This application is a continuation of my 15 application Serial No. 411,519, filed September 20th, 1920.

This invention relates to a process and the 20 related apparatus for copying notes from stenographers' note books when transcribing same by means of a typewriter, and has for its object the production of a new and novel device and an improved process of using the same, whereby the notes of the 25 stenographer may be read and transcribed with a minimum expenditure of time and trouble, and with greater ease in manipulation of the note book than has heretofore been possible.

An object of the invention is the provision 30 of an attachment for typewriters whereby a stenographers' note book may be held in position over the typewriter so that the shorthand notes therein may be readily read and transcribed and with a minimum 35 of errors due to the accidental skipping of lines or pages.

A further object of the invention is the provision of a stenographers' note book which when used by this improved process 40 constitutes a more efficient method of taking and transcribing notes in shorthand.

A still further object of this invention is the provision of a device and a process of using the same, wherein the note book of 45 the stenographer is always retained in a compact, handy and convenient position, the leaves being at all times securely held from fluttering or dropping back over the matter to be transcribed.

An important object of the invention is 50 the provision of a device and a process in connection therewith which automatically brings into position the following leaf of a stenographers' note book after one leaf 55 has been entirely transcribed.

Other and further important objects of this invention will be apparent from the disclosures in the accompanying drawings and specification.

The invention (in a preferred form) is 60 illustrated in the drawings and hereinafter more fully described.

On the drawings:

Figure 1 is a plan view of the improved 65 attachment for typewriters showing a note book in position thereon.

Figure 2 is a side elevation thereof with the note book partly broken away.

Figure 3 is a section through the attachment and note book upon a reduced scale. 70

Figure 4 is a fragmentary plan view of a pair of leaves of the note book.

Figure 5 is a sectional view through the attachment showing the note book in a different position. 75

Figure 6 is a sectional view showing the note book in still another position.

Figure 7 is a plan view of the note book.

As shown on the drawings:

In carrying out the novel process of this 80 invention, it is contemplated that the stenographers' notes be recorded in a note book such as is illustrated in Figure 7, by writing across the page from the top to the bottom thereof and downward across the front surface of the adjacent rear leaf, and starting from the rear of the note book. Thus in Figure 7 is shown a note book assumed to have fifty pages numbered consecutively 85 from the front of the book. While notes may be recorded on the fiftieth page, it is better to begin recording notes upon page 48 and continuing down page 49 until the same is filled. Page 48 may then be turned and the notes continued on page 46 and across 90 page 47, etc.

In transcribing notes recorded in the above manner, the note book is caused to intermittently travel in an oblong or similar path to allow the notes to be transcribed 100 and to allow the leaves to be automatically turned during such travel for bringing the next page to be transcribed before the operator.

The apparatus illustrated for carrying 105 out this method comprises a stationary oblong member 1 made of celluloid or the like which is supported upon the flanges of channel members 2 positioned within the sides of the member 1 with the webs of the 110

channels directed inwardly whereby a runway is formed in each side of the oblong member. Tie rods 3 may connect these channel members to maintain the same in proper spaced relation.

Suitable bearings are secured to the webs of the channel members adjacent the ends thereof, and suitable apertures are made in the webs in alignment with said bearings for 10 receiving the forward and rear shafts 4 and 5, both ends of which extend into said runways and support sprocket wheels 6 rigidly secured thereto. Endless members in the 15 form of sprocket chains 7 are trained over these sprockets and operate in said runways, being substantially concealed therein so that they are not likely to cause injury. The forward shaft 4 projects beyond one side of the oblong member 1 where it is provided with 20 an operating knob 8 which may be grasped by the hand and rotated for simultaneously rotating the sprocket chains 7.

A note book holder is connected at its opposite ends to the sprocket chains 7 and 25 travels over the surface of said oblong member 1. This note book holder is illustrated as consisting of a bar 9 having returned bent ends which extend into the runways and which are suitably secured to the sprocket 30 chains. Suitably spaced lugs 10 may be slidably supported upon the bar 9 and clamping or clasping members 11 may be pivoted to these lugs and constrained toward clamping action by means of springs (not 35 shown), as is usual in such forms of clamps or clasps. The note book is adapted to be inserted between the clamps which may be raised by pressing on the ends thereof and which may be properly adjusted by sliding 40 the lugs 10 on the bar 9, as is obvious. These clamping members will press the note book against the bar 9 and cause it to travel with the bar 9 as the same is caused to travel around the oblong member or support 1.

45 The oblong support 1 is adapted to be supported upon a base 12 by means of end brackets 13 which are provided at their upper ends with journal bearings to receive the ends of the shafts 4 and 5, said base 50 being adapted for attachment to a typewriter. A pair of swinging arms 14 are pivoted at their lower ends to the two forward brackets 13, and the upper ends of 55 these arms carry a marker 15 which is in the form of a thin flat bar which spans the support 1, and serves as a guide under which the note book is confined, besides indicating the line of notes to be transcribed. One of the arms 14 may be provided with a handle 60 16 for swinging the guide and marker 15 which may be swung so that it will adjust itself to the thickness of the note book passed thereunder, as can be readily seen by viewing Figures 5 and 6, the former of which 65 illustrates a plurality of leaves held under

the guide and marker 15, while the latter shows a single leaf so held.

When my novel method of operating the note book for transcribing the notes is used in connection with the above described apparatus, the note book is positioned under the marker 15 with the first page of notes which is represented by the numeral 48 in view. The upper end of the note book is then clamped upon the conveyor bar 9, as shown in Figure 2. Then by properly rotating the knob 8 and its shaft 4, the front sprocket will be rotated and cause the chains to travel around the sprockets. As the chains travel, they carry the note book holder 9 around the surface of the oblong support, as is obvious. After the note book has been secured, as shown in Figure 2, it is rotated around the oblong support until it is substantially in the position shown in Figure 5 when the marker 15 may rest under the first line of notes to be transcribed upon the typewriter, and the leaf containing page 49 is traveling along behind the leaf containing page 48. When the first line of page 48 has been transcribed, the knob 8 is turned to advance the note book another line and so on until the last line of page 48 has been transcribed. The leaf containing page 48 may now be released by the clasps 11 which will then engage the leaf containing page 46. Page 49 which follows page 48 may now be transcribed by intermittently rotating the knob 8, as is shown in Figure 6. As page 49 is being thuswise transcribed, leaf containing page 48 will dangle from the note book as shown in Figure 6, while leaf containing the page 46 is passing beneath the oblong support so that page 46 will follow page 49 in the transcribing process. When page 46 is being transcribed, leaf containing pages 47 and 48 will be trailing along under the oblong support with page 47 facing downwardly so as to follow page 46 in the transcribing process.

Thus, it will be apparent that page 48 is first transcribed, then page 49, page 46 and page 47 in succession, and that after page 48 has been transcribed and released, its leaf will be automatically turned during the operation of the note book so that the reverse side or page 47 will follow page 46 which should be leaf containing the transcribed before page 47.

The leaves of the note book are preferably bound by some flexible material which may readily permit the note book to travel around its oblong support. It will be appreciated that two pages of notes are transcribed without turning a leaf, and that a transcribed page is automatically turned so that its reverse side or page may follow in consecutive order the taking of the notes. The pages are thuswise automatically set in consecutive order according to the taking of the notes.

I am aware that numerous details of construction may be varied through a wide range without departing from the principles of this invention, and I therefore do not 5 purpose limiting the patent granted otherwise than is necessitated by the prior art.

I claim as my invention:

1. The method of handling leaves flexibly connected together at one end, which consists in clamping together all but the top leaf thereof, then causing them to travel in an unbroken path, and at the completion of each cycle of movement unclamping the top clamped leaf only.
- 10 2. The method of handling leaves flexibly connected together at one end, which consists in clamping together all but the top leaf thereof, then causing them to travel intermittently in an oval path with said top leaf trailing, and at the completion of each cycle of movement unclamping the top clamped leaf so that it will trail during the next cycle of movement.
- 15 3. In an apparatus of the class described, a support, a note book having its leaves flexibly connected together at one end, releasable laterally adjustable clamps for

said book, and an endless traveling member in said support to which said clamps are connected.

4. In an apparatus of the class described, an oblong support, and means for clamping a note book thereon and causing the same to travel around said support, comprising a book clamping member spanning said support and having downwardly and inwardly extending ends, and endless traveling members connected to the ends of said member.

5. In an apparatus of the class described, a hollow oblong support, channel members secured in the sides of said support for forming concealed runways, rotatable members rotatably supported in said runways, endless members trained over said rotatable members, and a book support secured at its ends to said endless members.

In testimony whereof I have hereunto subscribed my name in the presence of two subscribing witnesses.

CLARENCE H. CALDWELL.
